TYPEWRITING MACHINE

Robert Thomas Pollock, New York, N. Y., assignor
to Joseph Lee Sweeney, New York, N. Y.

Application June 13, 1941, Serial No. 397,886

23 Claims. (Cl. 197—9)

This invention relates to typewriting machines and particularly to typewriting machines which are intended to print a plurality of characters simultaneously on a paper strip.

One of the principal objects of the invention is to provide a small compact typewriting machine of the type in which a plurality of characters may be simultaneously printed on a paper strip, the outside dimensions of the machine being but slightly larger than the area of the keyboard.

Another object of the invention is to provide a typewriting machine for printing a plurality of characters simultaneously on a paper strip in which the paper strip is fed into the side of the machine.

Another object of the invention is to provide a typewriting machine for printing a plurality of characters simultaneously on a paper strip in which the types are positioned at the side of the keyboard and the paper strip is fed into the side of the machine, the printing being done along a line which extends from front to back of the machine.

Another object of the invention is to provide a typewriting machine in which a plurality of types are arranged to print in a line extending from front to back of the machine, the connection between the types and keys being such that the printing order of the types from front to back may be independent of the order of the keys.

Still another object of the invention is to provide a small compact typewriting machine with keys which have a substantially straight-line motion, so that the angle of a key does not change materially when the key is operated.

Another object of the invention is to provide a typewriting machine with a plurality of types operated by bars arranged side by side and transversely to the planes of operation of the keys.

Still another object of the invention is to provide a typewriting machine, as defined in the last paragraph, with means to shift the type bars so as to print other types associated with the bars.

Other objects of the invention will in part be obvious and will in part appear hereinafter.

The invention accordingly comprises the features of construction, combinations of elements, and arrangement of parts, which will be exemplified in the constructions hereinafter set forth, and the scope of the application of which will be indicated in the claims.

For a fuller understanding of the nature and objects of the invention reference should be had to the following detailed description taken in

connection with the accompanying drawings, in which:

Fig. 1 is a plan view of a typewriting machine embodying my invention with portions of the casing removed for clearness;

Fig. 2 is a sectional plan view showing the mounting of the type bars, types, and platen, the section being taken on the line 2—2 of Fig. 3;

Fig. 3 is a front sectional view taken on the line 3—3 of Fig. 1;

Fig. 4 is a fragmentary front view of the machine showing the shift mechanism in actuated position;

Fig. 5 is a sectional end view of the typewriter taken substantially on the line 5—5 of Fig. 1;

Fig. 6 is a sectional end view taken on the line 6—6 of Fig. 1 just beyond the platen and showing the types;

Fig. 7 is a sectional end view taken on the line 7—7 of Fig. 1;

Fig. 8 is an enlarged fragmentary sectional view taken on the line 8—8 of Fig. 1 and showing one of the vowel keys depressed together with one of the consonant keys;

Fig. 9 is a rear view partly in section of the typewriting machine;

Fig. 10 is an isometric view of the key lever mechanism; and Fig. 11 is a fragmentary view of a type bar illustrating the manner in which it is operated.

As has already been stated, the invention is particularly applicable to a typewriting machine which is adapted to print a plurality of characters simultaneously across a paper strip. Such a machine is a stenotype machine in which the characters thus printed across the paper strip represent words or syllables in accordance with a stenotype code. In stenotype machines heretofore used, a paper strip is fed from front to back of the machine, the platen being positioned at the rear, spaced from the keyboard, and the key levers and type bars being positioned in the space between the platen and the keyboard. The keyboard is necessarily of a certain general size because it is limited by the size of the human hands. Keys must necessarily be large enough to be manipulated by the fingers and they must be far enough apart so that when any given key is struck intentionally an adjoining key is not likely to be struck erroneously in conjunction with it. Therefore, if such a typewriter is to be made smaller and more compact, the keyboard can not be decreased in size below the minimum size as defined by the size of the hands and fingers. I have found, however, that I can make

such a machine much smaller and more compact, and thus attain one of the principal objects of the invention, by feeding the paper strip into the machine in a direction transverse to the usual direction of feeding such paper strip, and providing the platen and types at the side of the keyboard. A novel arrangement of key levers and type bars makes this possible and provides a machine which is but little larger than the actual size of the keyboard.

The machine of my invention comprises a frame formed of two end plates 12 and 13 (Figs. 1, 3, and 6) which are held in spaced relation by rods 14 and 15 at the lower ends thereof and rods 16 and 17 at the upper ends, the rods being attached to the plates in any suitable manner. The plates 12 and 13 are cut away so that they have the appearance of an inverted U, and both slope upwardly from front to back of the machine, as indicated in Fig. 6. The cut away portion of the plate 12 provides downwardly extending front and rear members 18 and 19 which may be flanged to receive rubber feet 20 and 21 respectively. Similarly the cut away portion of the plate 13 provides front and rear members 22 and 23 which are flanged to receive rubber feet 24 and 25 respectively. The plate 12 which is at the left side of the machine is provided with arms 26 and 27 which extend towards the left at right angles to the plate for the purpose of supporting the platen 28 and associated mechanism. The platen may consist of a rubber covered roller, and is mounted on a shaft 29, the ends of which pass through suitable holes in the members 26 and 27 and may be secured against longitudinal movement by split washers 30 and 31 which fit into grooves on the ends of the shaft.

The platen is mounted near the bottom of the machine and a plurality of type bars 32 (Figs. 2, 3, 4, 6, 7, 8, and 10) are mounted side by side perpendicular to and in substantial alignment with the platen shaft. These type bars extend completely across the machine under the keyboard through the cut away portions of the plates 12 and 13, and are mounted for longitudinal movement. To this end the plate 13 is provided with flanges 33 and 34 which are spaced apart, as indicated in Fig. 2, and support between them a bar 35 which is provided with transverse parallel grooves 36, equally spaced along its length. The bar 35 may be held in place between the flanges 33 and 34 by suitable screws 37 and 38. The right ends of the type bars 32 are provided with longitudinal slots 39 (Figs. 3 and 4) through which the bar 35 extends, and the edges of the slots fit into the grooves 36 and thereby space the right hand ends of the type bars, at the same time permitting longitudinal movement thereof. The other ends of the type bars are provided with slots 40 through which a rod 41 passes, the rod being supported between flanges 42 and 43 which extend outwardly towards the left from a plate 44 mounted in the machine in a manner to be hereinafter described. Suitable separators 45 are provided on the rod 41 to maintain the ends of the type bars 32 in spaced relation.

I make the bars 32 out of sheet metal and place them edgewise in the machine, and in order to strengthen the bars, I prefer to give them a configuration shown in Figs. 7 and 8, the upper part of the bar being flat, while a bead 46 is provided adjacent the lower edge of the bar extending substantially the length

thereof. In addition, the lower edge of the bar is bent at right angles, forming a flange 47, this construction insuring a rigid type bar which will not bend under conditions of operation.

The left hand end of each type bar is provided with at least one type 48 while certain of said bars have a pair of types 48 and 49, the former above the latter, the type 48 being in position to print when the type bar is moved towards the platen in the normal position of the plate 44. Means, to be hereinafter described, is provided to raise the plate 44, so as to cause the types 49 to print when the type bars are moved towards the platen.

A suitable inked ribbon 50 is provided and is caused to move in a manner to be hereinafter described between the types and the platen, and a paper strip 51 is caused to be fed over the platen in a manner also to be hereinafter described.

The type bars 32 are individually urged towards the right side of the machine by means of flat springs 52 (Figs. 4 and 6) which are supported on the plate 44 by means of a bar 53 held in place by suitable screws 54. These flat springs 52 extend downwardly from the top of the plate and enter slots 55 in the upper edge of the type bars 32. Longitudinal movement of any type bar towards the platen will cause the associated spring 52 to be bent to the left, whereupon removal of the force acting on the type bar will permit the spring to return the type bar to its normal position towards the right of the machine. The left end of the slot 39 of each bar determines its limit of movement towards the right, while the type itself, striking against the ribbon and paper, backed up by the platen, determines the limit of movement to the left.

The machine used for illustrating the invention is intended to be used to record characters and groups of characters to represent sounds in accordance with the principles of stenotypy, the upper row of types on the type bars being arranged in the following order from front to back of the machine:

S T K P W H R N Y A O * E U F R P B L G T S D S

In order to move these types against the platen, a plurality of keys 60 (Fig. 1) are arranged in two rows in the following order across the keyboard:

S T P K N * F P L T D
S K W R Y R B G S S

The middle key in the upper row is used to operate the type bar carrying the star. There is also a middle key in the second row which is used solely to feed the paper strip, in a manner to be hereinafter described, and does not have any type associated with it. The keys at the left of these two rows are intended to be manipulated by the fingers of the left hand, while those at the right are intended to be manipulated by the fingers of the right hand.

Four vowel keys 61 are also provided in front of the other two rows of keys at the center of the machine and are to be operated by the thumbs.

The keys may have the characters printed on them, as indicated in Fig. 1, or they may be left entirely blank to depend on manipulation by the "touch" system.

The keys are associated with type bar actuating members 62, 75, and 81 which are best shown in Fig. 8. These members are substantially alike

although some of them are mounted in one position while others are reversed. The members normally are aligned in the machine and each moves downwardly when its associated key is depressed. In Fig. 8 two of the keys are shown depressed with the associated type bar actuating members in their lowermost position. Each of the keys 60 in the foremost row is mounted on a type bar actuating member 62 which comprises an elongated base portion 63 and an upwardly and forwardly extending arm 64 which supports the key at the top. This member 62 is mounted for substantially straight-line vertical movement in the frame of the machine by means of two levers 65 and 66. The lever 65 has one end pivoted at 67 to the upper portion of the member 64 while its other end is pivotally mounted on the rod 16. The lever 66 has one end pivotally connected at 68 to about the center of the lower portion of the member 64, while its other end is pivoted on the rod 17. The pivot point 68 is spaced below the pivot point 67 and slightly to the rear of it.

When the key is depressed both levers 65 and 66 move downwardly about the rods 16 and 17 and the type bar actuating member 62 will also move downwardly with substantially straight line motion. The angle of the key surface, therefore, remains substantially the same.

Various means may be employed to transmit motion from the members 62 to the type bars. In the embodiment of the invention illustrated a finger 69 is provided extending downwardly from the lower edge 63 of the member 62, and this finger is positioned at such a point along the edge that it will engage with a cam slot 70 (Figs. 4 and 11) in the particular type bar which that key is designed to operate. As illustrated in Fig. 8, the finger 69 on the key 60 at the extreme left of the foremost row of keys is arranged to operate the second type bar from the front when the actuating member 62 moves downwardly so that the finger can engage the slot in the type bar. The type bar slot 70 (Figs. 4 and 11) is designed so as to cause rapid movement of the type bar in the direction of the platen when the finger is pressed down into it, and then to slow up in its movement towards the platen, whereupon the force against the platen is increased by the further movement of the finger.

The keys in the rearmost row are supported on a reversed type bar actuating member 75, which is like the member 62, except that the upper portion 76 extends rearwardly instead of forwardly. This member 75 is supported on two levers 77 and 66, the former being pivoted on the rod 16 with its other end pivoted at 79 to the member 75, while the latter is pivoted on the rod 17 and has its other end pivoted at 80 to the center of the lower portion of the member 75. The movement of the members 62 and 75 connected respectively to one of the keys 60 in the foremost row and one of the keys 60 in the rear row is substantially the same when the keys are depressed, the downwardly extending fingers on both members 62 and 75 engaging the cam slots in the type bars 32 which the keys are designed to actuate. The member 75 in Fig. 8 is attached to the extreme left key on the upper row of keys 60, and the finger 69 shown on that member engages the foremost type bar 32.

The mounting of the vowel keys 61 is slightly different, although the principle is practically the same. The type bar actuating members 81 for the vowel keys are similar in shape to the members

62 except that they do not extend up as far, since the keys 61 are supported on the extending forward ends of levers 82 which serve the same purpose as the levers 65, connected to the type bar actuating members 62, and are pivoted on the rod 16 with their center portions pivoted at 83 to the upper ends of the members 81. The central lower portion of each of the members 81 is pivoted to one of the levers 66. By depressing one of the keys 61, the associated lever 82 swings about the rod 16 and the member 81 connected to it moves downwardly together with the lever 66 which maintains the member 81 in substantially straight line motion.

When the pressure is removed from the keys 60 and 61, the members 62, 75, and 81 are raised again to their normal upper position by means of springs 84 which are connected between forwardly extended ends 85 of the levers 66 and the spacing rod 15. In order to secure the lower ends of these springs, the spacing rod 15 is provided with slots 86 spaced across the upper surface of the bar and a slender rod 87 is fitted into a longitudinal slot which extends the entire length of the rod 15 and across the slots 86. The slender rod 87 is held in position by tamping the edges of the slot in which it is inserted. Each of the springs 84 has its lower end looped around the slender rod.

The two rows of keys 60 are spaced at approximately equal intervals from side to side of the machine, and this means that the levers 65, 77, and 66 which support the type bar actuating members associated with these keys are substantially equally spaced along the rods 16 and 17. The vowel keys 61, however, are also supported in a similar manner, and therefore the levers 82 and 66 which support these keys come between the others on the rods 16 and 17. The spacing 30 is maintained on the rod 16 by means of sleeves 88 which are secured to the rod 16 by any suitable means. In like manner the levers 66 on the rod 17 are spaced by means of the sleeves 89 which are also secured to the rod 17 in any suitable manner. The type bar actuating members 62, 75, and 81 have relatively large bearing surfaces with the levers which support them, and in all cases the pivots 67, 68, 79, 80, and 83 hold these parts in close contact with each other to prevent sidewise movement of the keys. Also the sleeves 88 and 89 support the levers on the rods 16 and 17 respectively so as to prevent sidewise motion. This insures that each type bar actuating member will move straight down, so that the operating finger on the lower edge thereof can push the type bar towards the left without movement of the type bar actuating member in the opposite direction.

The return of the keys to their normal position 60 is cushioned by means of a channel member 95 which is supported between the end plates 12 and 13 by attaching to suitable flanges 96 and 97 with screws 98 and 99. This channel 95 contains a felt pad 100 which is engaged by the upper surface of the type bar actuating members 62, 75, and 81. If desired a pad 101 of rubber or other suitable resilient material may be provided on the upper surface of the channel member 95 so as to form a cushioned downward limit of movement of the keys and associated mechanism. As shown in Fig. 8, this cushioning surface will be struck by the levers 65, 77, and 82 when the keys reach their lower limit of movement.

Between successive depressions of the keys the

paper strip is caused to move the proper distance through the machine so that the printed characters appear on successive lines on the paper. For this purpose every one of the keys is caused to operate the feeding mechanism, so that regardless of which key is depressed alone or what group of keys is depressed, the paper strip will always advance the proper distance. In order to accomplish this, I provide a feeding mechanism which comprises a bail 102 which is formed integral with a shaft 103 rotatably supported between the two plates 12 and 13, the restricted ends of the shaft 103 passing through suitable holes provided for that purpose in the plates. The shaft is positioned at the rear of the machine beneath the spacing and pivoting rod 16, and the bail extends forwardly so that its normal position is beneath the rear corners of the type bar actuating members 62, 75, and 81. The lowermost corners of these members are curved as indicated at 104 in Fig. 8 so that when these type bar actuating members move downwardly they strike the bail 102, causing the shaft 103 to rotate in a clockwise direction, as seen in Fig. 8. The rear ends of the type bar actuating members slide over the edge of the bail 102, so as to turn the bail to its lowermost position and hold it in that position before the type bar actuating members have reached their lower limit of movement.

The left hand end of the bail 102 is bent at right angles to form a lug 105 which is provided with a hole 106 adapted to receive a pin 107. This pin is rigidly secured to a short auxiliary shaft 108 which is rotatably mounted parallel with the left end plate 12 between the arm 26 and a bracket 109 secured to the plate 12 by means of screws 110. At the rear end of the shaft 108, I provide a lever 111 which is rigidly attached to the shaft and extends towards the left. The end of the lever 111 is connected by means of a link 112 to a pawl 113 which is mounted for movement about the platen shaft 29 on an arm 114. The pawl is pivoted to the member 114 at 115. The pawl engages a ratchet wheel 116 which is attached to the platen. When the bail 102 is pushed downwardly, by means of any one or more of the keys, the pin 107, engaged by the hole 106 in the lug 105, will cause the shaft 108 to rotate in a direction to swing the lever 111 upwardly, thereby raising the link 112 and causing the pawl 113 to rotate the platen 28 through an angle corresponding to one tooth of the ratchet wheel 116. The bail 102 is raised to its normal position after the pressure on the key or keys is removed by a spring 117 which is attached to a pin 118 extending outwardly from a lug 119 formed on the right hand end of the bail, as viewed in Fig. 3.

The paper strip 51 feeds into the machine below the platen 28 and out again over the top of the platen. In order to insure ease in inserting the strip into the machine, I provide a pair of roller sleeves 125 on a shaft 126 which extends between downwardly extending lugs 127 and 128 on the arms 26 and 27 respectively. The shaft 126 may be held in position in any desirable manner. As paper is fed over the rollers 125, it is guided by a plate 129 which is pivotally mounted upon a shaft 130 and is urged by a suitable spring 131 (Fig. 5) in a clockwise direction, as viewed in Fig. 9, so that the inner edge of the plate 129 bears resiliently against the platen 28.

At the upper surface of the platen 28, I provide a small guide roller 132 which is mounted

on a shaft 133 rotatably supported in a bracket 134. This bracket has downwardly extending side arms 135 which are pivotally mounted on the shaft 126. A spring 136 which is wrapped around the shaft 126 causes the bracket 134 to be urged in the direction of the platen so as to maintain the roller 132 in contact with the platen. The bracket 134 is, however, movable away from the platen against the tension of the spring 136, so as to permit the insertion of the paper. A lug 137 is provided on one of the arms 135 of the bracket 134 which engages the outer end of the plate 129 so as to raise the outer end when the bracket 134 is moved downwardly, and this separates the inner end of the plate 129 from the platen so as to permit the end of the paper strip to be slipped between it and the platen when inserting. The lower edge of the bracket 134 is provided with sharpened teeth 138 to permit the paper to be easily torn off against this edge when it is desired to remove a section of the paper. An apron 139, supported between the two lugs 127 and 128 on the arms 26 and 27 respectively, separates the outgoing end of the paper from the incoming portion.

It will be seen that with the paper feeding mechanism just described, the platen will be turned to move the paper strip in the machine whenever one or more of the keys is depressed. However, the arrangement is such that the feeding mechanism will stop before the types have reached the platen. This is caused by the type bar engaging members passing over the edge of the paper feed bail before the keys have reached their limit of movement. The movement of the paper thus stops while the types continue to move towards the platen and when the types strike, the paper is stationary.

It is also desirable at times to feed the paper strip without printing any of the types, and I therefore provide a key 140 (Fig. 1) at the center which is mounted on a member 141 and associated levers 65 and 66. The member 141 is similar to the type bar actuating member 62 except that there is no finger extending downwardly from it, as indicated in Fig. 4, and hence none of the type bars are actuated by it. The member 141, however, does push the feeding bail 102 when it is depressed, just as all of the type bar actuating members do, and hence when the key 140 is depressed, the platen is caused to rotate one notch of the ratchet wheel 116.

In the machine used for illustrating this invention, the shift key 145 is intended to be used when it is desired to print numerals. Therefore, the lower row of types 49 (Fig. 2) are arranged as follows from front to back of the machine:

1 2 3 4 5 ¶ 6 7 8 9 0

Since there are 11 keys across the keyboard, the extra one may be used to produce some other desired character designation, such as the paragraph mark shown. Only those type bars which are associated with the rearmost row of keys 60 are provided with the lower types 49, the other type bars having no lower types thereon.

In order to shift from the upper row of types 48 to the lower types 49, I provide an elongated shift key 145 which is supported upon a pair of plates 146 and 147 mounted at the rear of the machine for vertical movement. The key 145 extends the entire width of the keyboard and is placed just at the rear of the rearmost row of keys 60, so that it may be depressed with any one

or more of the keys 60. Both plates 146 and 147 are provided at their lowermost ends with slots 148 and 149 respectively in which fits the lowermost spacing rod 16, suitable slots being provided in that rod to accommodate the plates 146 and 147, so as to permit vertical longitudinal movement but to maintain the plates in their proper position in the machine. The upper ends of the plates 146 and 147 are provided respectively with slots 150 and 151 (Figs. 3, 7, and 8) which are adapted to fit over the upper spacing rod 16, suitable spacers being left between the sleeves 88 of this bar to accommodate the plates 146 and 147. These slots 150 and 151 are curved so that when the key 145 is depressed, it will follow the movement of any key in the rearmost row. This avoids any chance of pinching the fingers between the elongated key 145 and any of the keys of the rearmost row which may be depressed with it.

The plates 146 and 147 are also attached to the spacing rod 16 by means of arms 152 and 153 which are pivoted to the rod 16, the arm 152 being adjacent the plate 146 and the arm 153 being adjacent the plate 147. The outer ends of the arms 152 and 153 carry a rod 154, the ends of which pass through horizontal slots in the plates 146 and 147, respectively, of which the slot 156 in the plate 147 is shown in Fig. 8. The rod 154 can move from front to back in these slots when the key 145 is moved up and down. Both plates 146 and 147 are cut out at 157 to avoid contact with the shaft 103 for the feeding mechanism, as will be clearly seen from Fig. 8.

The plate 147 is provided with a notch 158 at its lower forward edge, and this notch is adapted to receive the end of an arm 159 which is pivoted to a lug 160 bent inwardly from the plate 12, the arm being pivoted to the lug by means of a screw 161. The arm 159 extends through the lower opening in the plate 12 and engages a notch 162 in the plate 44 which carries the bar 41 for supporting the printing ends of the type bars. The plate 44 has an upper extension 163 at the rear and a lower extension 164 also at the rear of the plate. These extensions are provided respectively with slots 165 and 166. The slots 165 and 166 fit over grooved members 167 and 168 respectively which are attached in any desired manner to the plate 12, and the plate 44 is therefore held in spaced relation from the plate 12 by the members 167 and 168. The plate 44 is cut out at the rear as indicated at 169 (Fig. 6) to clear the arm 26 and the arm 111 and link 112 for the feeding mechanism. The members 167 and 168 support the plate 44 against angular movement to permit it to have a limited vertical movement by means of the slots 165 and 166. The forward end of the plate 44 is guided in a slotted member 175 which is part of a bracket 176 used for supporting a part of the ribbon mechanism which will be later described.

A lug 177 (Fig. 6) extending forwardly from the upper extension 163 of the plate 44 is provided with a spring 178, the lower end of which is attached to a lug 179 on the felt cushioning channel 95. The spring tends to urge the plate 44 normally downwardly, but upon depressing the elongated key 145, the arm 159 is rotated about the screw 161, so as to raise the plate 44, which in turn raises the type bars 32, bringing the lower row of types 49 into alignment with the platen and causing them to print on the paper when the keys are depressed so as to move the type bars longitudinally towards the platen.

The shift key 145, when operated alone, merely shifts the position of the left hand ends of the type bars to place the lowermost row of types in position for printing. However, when any one or more of the rear row of keys 60 is depressed with the shift key 145, the type bars are first shifted and then the type bars associated with the depressed keys are moved against the platen to print. The arrangement of the parts is such that the shift mechanism completes its movement before the types strike the platen.

The return of the key 145 and plate 44 to their normal positions after the pressure is removed from the key is cushioned by means of a rearwardly extending flange 180 (Figs. 2 and 9) on the arm 159. This arm is arranged to strike against a felt pad 181 provided in a bracket 182 held against the inside of the plate 12 by means of suitable screws 183.

When the shift key 145 is operated, it will be apparent that the type bars 32 are nearer the type bar actuating members 62, 75, and 81, especially those at the left side of the machine where the type bars move through the greatest distance to reach the shifted position. This means that the keys will not have to be depressed as far to cause the type bars to print as when the type bars are in their normal position. However, this difference in movement of the keys does not interfere with the operation thereof.

Any type of inked ribbon may be used with the machine of the invention and any type of feeding mechanism may be used for advancing the ribbon between the types and platen as the machine is operated. In order to illustrate the invention, I have shown a continuous ribbon 50 which is arranged to move around the frame of the machine and to be driven by the paper feed mechanism. To this end a roller 186 (Figs. 1, 2, and 6) is rotatably mounted on a vertical axis between the bracket 176 and a small bracket 187 provided for that purpose on the arm 27. The roller 186 is preferably provided with a felt pad 188 which contacts with the ribbon and which absorbs ink supplied to it so as to keep the ribbon moistened with ink as it passes over the roller. The roller is mounted so that the left side of the pad 188 is aligned with the space between the platen and the types when the types are in their normal position, so that the ribbon can move without touching the types or platen. At the rear of the machine, I provide an idler roller 189 (Figs. 2 and 9) which is rotatably mounted on a bracket 190 (Figs. 2 and 5) attached to the arm 26. Another idler roller 191 (Figs. 2 and 6) is rotatably mounted between the lower edge of the arm 26 and a bracket 192 which is provided for that purpose and is attached to the end plate 12. This permits the ribbon to pass around the rear of the plate 12, as is indicated in Fig. 2.

I also provide a tensioning device for the ribbon which is mounted on a bracket 193 (Figs. 1, 2, 3, and 9) attached in any suitable manner to the lower space rod 14. A rearwardly extending flange 194 on the bracket carries an idler roller 195 on the right end of the bracket, while another rearwardly extending flange 196 on the left end of the bracket carries a depending idler roller 197. These two rollers are aligned with each other and carry flanges to prevent the ribbon from slipping off of them. A movable arm 198 is pivotally mounted on the flange 194 and carries a depending roller 199 at its outer end, the arm 198 being of sufficient size to swing within the flange 196, so that the roller 199 will come be-

tween the two rollers 195 and 197. A spring 200 is connected between an upstanding pin 201 on the outer end of the arm 198 and a lug 202 attached to the flange 194, the arrangement being such that the spring tends to swing the arm and roller 199 away from alignment with the two rollers 195 and 197. The ribbon 59 passes in back of the roller 197, in front of the roller 199, and in back of the roller 195, with the spring tending to pull the spring and roller 199 away towards the front. This maintains a suitable tension on the ribbon at all times.

Another idler roller 203 (Figs. 2 and 9) is rotatably mounted in a cut-out portion 204 in the end plate 13, suitable guides 205 being provided above and below the roller to prevent the ribbon from slipping off of the roller. Additional rollers 206, 207, and 208, which are similar to the roller 203, are mounted at the ends of flanges 33, 34, and the forward end of the end plate 13, respectively, to guide the ribbon around the right end of the machine. The ribbon extends from the roller 208 back to the inking roller 186.

The ribbon is driven by driving the roller 186 from the platen. To this end the roller 186 is provided at its upper end with a suitable gear 209 (Fig. 1) which meshes with a gear 210 carried by an auxiliary shaft 211. A bevel gear 212 at the other end of the auxiliary shaft meshes with a bevel gear 213 on the platen shaft. At any time that the platen rotates the ribbon roller 186 is rotated through this gear connection. Since the platen is always stationary when the types strike, the ribbon will also be stationary.

The entire machine with the exception of the keys, and the platen, and paper guide rollers may be enclosed in a casing 214 which may be attached to the end plates in any desired manner, as by supplying suitable flanges 215 for that purpose. This casing is preferably made to conform as closely as possible to the configuration of the machine, so as to maintain the compact form, while at the same time allowing the keys to be available for manipulation by the operator.

From the above description it will be seen that I have provided a typewriting machine for printing simultaneous characters across a paper strip which is so compact that it is only slightly larger than the keyboard itself and through which the paper strip is fed from the side of the machine. The outgoing paper strip passing off the top of the platen is always convenient to the operator who can pick it up and examine it without reaching across the machine. The consonant keys have a substantially straight line motion so that they are easy to operate, and they are also arranged so that two keys in the same row from front to back of the machine may be operated simultaneously by the same finger. The shift key can also be operated simultaneously with any of the keys of the rear row with the same finger that operates that particular key.

Attention is again drawn to the fact that the order of the keys is independent of the arrangement of types from end to end of the platen. All of the type bar actuating members associated with the keys cross all of the type bars and hence any key on the keyboard may be made to operate any type bar by providing the finger 69 in the proper position above that particular type bar and providing that particular type bar with a cam slot to cause the bar to move longitudinally when the finger passes down into the slot. For this reason, it is possible to arrange the order of the

types from end to end of the platen, so as to print the particular code which the machine is designed to use, and at the same time to arrange the keyboard with the keys in the most convenient order for fast operation. Thus, letters or syllables which are used most frequently can be printed with the most convenient placing of the fingers on the keys.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which as a matter of language might be said to fall therebetween.

I claim:

1. In a typewriting machine for printing a plurality of type characters simultaneously across a strip of paper, a keyboard including a plurality of keys arranged for operation in vertical planes, a plurality of type bars mounted substantially directly beneath said keyboard and arranged side by side substantially at right angles to the planes of movement of said keys, the said type bars being substantially no longer than the distance between the outermost planes of operation of said keys, a type on the end of each type bar, said types forming a straight line, means to support a paper strip in position adjacent said types, so as to permit said types to strike said paper when said type bars are moved longitudinally in the proper direction, and separate means associated with each of said keys and cooperating with a separate type bar to cause the operation of a key to produce longitudinal movement of the associated type bar to print the type character thereon on said paper.
2. In a typewriting machine for printing characters simultaneously across a paper strip, a frame, a keyboard including a group of keys arranged in rows and mounted in said frame for operation in substantially vertical planes, said frame conforming in shape to the general outline of the group of keys and being slightly larger than said group of keys, a plurality of type bars arranged side by side substantially directly beneath said keyboard within said frame and substantially perpendicular to the planes of operation of said keys, the ends of said type bars lying in a straight line which extends from front to back of the machine, a type on the end of each type bar, means to support a paper strip in position to be struck by said types when said type bars are moved longitudinally in the proper direction, and separate means operatively connected with each of said keys and adapted to cooperate with a separate type bar to move a type bar towards said paper when said associated key is operated.
3. In a typewriting machine, a plurality of keys arranged to move in vertical planes, a plurality of type bars arranged side by side extending substantially at right angles to the planes of movement of said keys, types on the ends of said type bars, said types lying in substantially a straight line, means to support a paper strip in position to be struck by said types when said type bars

70

are moved longitudinally, and separate means operatively connecting each of said keys with one of said type bars, whereby the depression of said key will move said type bar longitudinally, said means comprising a cam slot on said type bar and finger operatively connected with said key to engage said cam slot.

4. In a typewriting machine a frame, a plurality of keys, means to mount said keys in said frame for movement in substantially parallel vertical planes, said means comprising substantially vertical key levers upon which said keys are supported and a pair of parallel lever arms for each of said keys pivoted to said frame and to each key lever, whereby when a key moves the angularity of the upper surface thereof does not substantially change, a plurality of type bars positioned side by side beneath said keys and substantially at right angles to the planes of movement thereof, a type on the end of each of said type bars, said types being in a straight line which is substantially parallel to the planes of movement of said keys, means to hold a strip of paper in a position to be struck by said types when said type bars are moved longitudinally, and separate means on each of said key mounting means to cooperate with a separate type bar to move said type bar longitudinally when the associated key is depressed, so as to print the type carried on the end of said type bar.

5. In a typewriting machine a frame, a plurality of keys, means to mount said keys in said frame for movement in substantially parallel vertical planes, said means comprising substantially vertical key levers upon which said keys are supported and a pair of parallel lever arms for each of said keys pivoted to said frame and to each key lever, whereby when a key moves the angularity of the upper surface thereof does not substantially change, a plurality of type bars positioned side by side beneath said keys and substantially at right angles to the planes of movement thereof, a cam slot in each of said type bars, a type on the end of each of said type bars, said types being in a straight line which is substantially parallel to the planes of movement of said types, means to hold a strip of paper in position to be struck by said types when said type bars are moved longitudinally, and means on each of said key mounting means to cooperate with a separate type bar to move said type bar longitudinally when the associated key is depressed, so as to print the type carried on the end of said bar, said means comprising a finger extending downwardly from said key mounting means and adapted to engage the cam slot in said type bar.

6. In a typewriting machine for printing a plurality of types simultaneously across a strip of paper, a frame, a plurality of keys mounted in said frame for movement in parallel vertical planes, a plurality of key levers, each of said keys being mounted on a key lever, a pair of parallel lever arms having one end of each pivotally mounted on said frame and the other end pivotally connected to said key lever, whereby said lever will have substantially straight line movement and the angularity of the key will not be altered when said key is moved, a plurality of type bars mounted side by side substantially perpendicular to the planes of movement of said keys, a type on the end of each of said type bars, said types being arranged in a straight line which is substantially parallel to the planes of move-

ment of said keys, means to hold a paper strip in a position so as to be struck by said types when said type bars are moved longitudinally in the proper direction, and means attached to said key levers and cooperating with said type bars to cause a type bar to move longitudinally when each key is depressed, so as to print the type carried by said type bar.

7. In a typewriting machine for printing a plurality of types simultaneously across a strip of paper, a plurality of keys mounted for movement in parallel vertical planes, a plurality of type bars arranged side by side and substantially perpendicular to the planes of movement of said keys, each of said type bars carrying a pair of types at the end thereof, said types being arranged in two parallel straight lines which are substantially parallel to the planes of movement of said keys, means to hold a paper strip in such position that it can be struck by one of said types on a type bar when said type bar is moved longitudinally in the proper direction, means connected to said keys and operatively associated with said type bars to cause a type bar to move in the direction of said paper when each key is operated, and means to shift the position of said type bars, whereby when the key associated with a type bar is operated, the type bar will move against said paper to print the other of said types carried by said bar.

8. In a typewriting machine for printing a plurality of type characters simultaneously across a strip of paper, a plurality of keys mounted for movement in parallel vertical planes, a plurality of type bars arranged side by side beneath said keys and substantially perpendicular to the planes of movement thereof, a pair of types on the end of each of said type bars, said types being aligned in two straight rows substantially parallel to the planes of movement of said keys, means to hold a paper in position to be struck by the types of one row when said type bars are moved longitudinally so as to cause said types to print, means connected to said keys and operatively associated with said type bars to cause a type bar to move longitudinally when each key is depressed, so as to print one of the pair of types carried on said type bar, a separate key, and means operatively associated with said separate key to shift bodily the said type bars, so as to cause said other type of said pair of types to print when the key associated with each type bar is depressed.

9. In a typewriting machine for printing a plurality of type characters across a paper strip, a plurality of keys mounted for movement in parallel vertical planes, a plurality of type bars positioned side by side substantially perpendicular to the planes of movement of said keys, each of said type bars having a pair of types on the end thereof and said types being so arranged and the ends of said type bars being so aligned that said types lie in two straight rows which are substantially parallel to the planes of movement of said keys, means to hold a paper strip in position so as to be struck by one of said types on a type bar when said type bar is moved longitudinally in the direction of said strip, each of said type bars being provided with a cam slot, and each of said keys being provided with a finger adapted to engage one of said cam slots when said key is moved to cause the associated type bar to move longitudinally so as to print one of the types carried thereby, a separate key,

and means operatively connected to said separate key to cause said type bars to shift bodily when said separate key is operated so as to print the other of said types when the key associated with a type bar is operated.

10. In a typewriting machine for printing a plurality of type characters across a paper strip, a plurality of keys mounted for movement in parallel vertical planes, a plurality of type bars positioned side by side substantially perpendicular to the planes of movement of said keys, each of said type bars having a pair of types on one end thereof, said types and bars being so arranged that said types lies in two straight rows which are substantially parallel to the planes of movement of said keys, means to hold a paper strip in position so as to be struck by one of said types on a type bar when said type bar is moved longitudinally in the direction of said strip, each of said type bars being provided with a cam slot, and each of said keys being provided with a finger adapted to engage one of said cam slots when said key is moved to cause the associated type bar to move longitudinally so as to print one of said types carried thereby, a separate key, and means operatively connected to said separate key to cause said type bars to shift bodily when said separate key is operated, so as to print the other of said types when the key associated with a type bar is operated, said type bars being beneath said keys.

11. In a typewriting machine, a plurality of keys arranged to move in substantially vertical planes, a plurality of bars mounted beneath said keys and arranged side by side substantially at right angles to the planes of movement of said keys, the said bars being substantially no longer than the distance between the outermost planes of operation of said keys, a plurality of types, means for operatively connecting each of said types with one of said bars, said types being arranged to form a substantially straight line, means to support a paper strip in position adjacent said types so as to permit said types to strike said paper strip when said bars are moved longitudinally in the proper direction, and means associated with each of said keys and cooperating with one of said bars to cause the operation of a key to produce longitudinal movement of the associated bar to print the type connected therewith on said paper strip.

12. In a typewriting machine for printing characters simultaneously across a paper strip, a frame, a plurality of keys arranged in rows and mounted in said frame for operation in substantially vertical planes, said frame conforming in shape to the general outline of the group of keys and being slightly larger than said group of keys, a plurality of bars arranged side by side beneath said keys within said frame and substantially perpendicular to the planes of operation of said keys, a plurality of types arranged side by side adjacent the ends of said bars, there being at least one type for each of said bars, means operatively connecting each of said types with a bar so as to cause said type to move when the associated bar is moved longitudinally, means to support a paper strip in position to be struck by said types when said types are moved in the proper direction, and means operatively connected with each of said keys and adapted to cooperate with one of said bars to move said bar so as to cause the type associated therewith to strike said paper when the key associated with said bar is operated.

13. In a typewriting machine for printing characters simultaneously across a paper strip, a

frame, a plurality of keys arranged in rows and mounted in said frame for operation in substantially vertical planes, said frame conforming in shape to the general outline of the group of keys and being slightly larger than said group of keys, a plurality of bars arranged side by side beneath said keys within said frame and substantially perpendicular to the plane of operation of said keys, a plurality of types arranged side by side adjacent the ends of said bars, there being at least one type for each of said bars, means operatively connecting each of said types with a bar so as to cause said type to move when the associated bar is moved longitudinally, a cam surface on each of said bars arranged substantially in the plane of movement of one of said keys, means to support a paper strip in position to be struck by said types when said types are moved in the proper direction, and means operatively connected with each of said keys and adapted to cooperate with the cam surface in the plane of movement thereof to move the bar carrying said cam surface so as to cause the type associated therewith to strike said paper when the key thus associated with said bar is operated.

14. In a typewriting machine, a frame, a plurality of keys, means to mount said keys in said frame for movement in substantially parallel vertical planes, said means comprising substantially vertical key levers upon which said keys are supported and a pair of parallel lever arms for each of said keys pivoted to said frame and to each lever, whereby when a key moves the angularity of the upper surface thereof does not substantially change, a plurality of bars positioned side by side beneath said keys and substantially at right angles to the planes of movement thereof, a type operatively associated with each of said bars, said types being arranged in a straight line which is substantially parallel to the planes of movement of said keys, means to hold a strip of paper in a position to be struck by said types when said bars are moved longitudinally, and means on each of said key mounting means to cooperate with one of said bars to move said bar longitudinally when the associated key is depressed, so as to print the type which is operatively connected to said bar.

15. In a typewriting machine, a plurality of first members arranged side by side in said machine and adapted to have individual limited movement in a predetermined direction, a plurality of second members arranged side by side in said machine transverse to said first members and adapted to have limited movement towards and away from said first members, there being one second member for each of said first members, means on one of each pair of said first and second members and having camming relation with the other member of said pair to cause that particular first member to move in said predetermined direction when the second member of that pair is moved, a plurality of types, there being a type for each of said first members, means to cause said types to print when said first members are moved, and individual means to move said second members.

16. In a typewriting machine a frame, a member, means to support said member in said frame for limited movement in a predetermined direction, said means comprising a pair of substantially parallel levers pivoted to said machine at different points therein and pivoted at spaced points on said member, the arrangement of said levers being such that said member has substantially straight-line motion in said predetermined

direction, a second member mounted for limited movement in a direction substantially at right angles to the direction of movement of said first member, means on one of said members and having camming relation with the other of said members to cause said second member to move when said first member is moved in said predetermined direction, a type, means to print said type when said second member is moved, and means to move said first member.

17. In a typewriting machine a first member, means to mount said first member for limited movement in a predetermined direction, a second member adjacent said first member, means to mount said second member for limited movement in a direction substantially perpendicular to said predetermined direction, a finger on said second member, said first member having a cam slot therein adapted to receive said finger, so as to cause said first member to move in said predetermined direction when said second member is moved towards said first member, a type, means to cause said type to print when said first member is moved, means to move said second member, and means associated with the mounting means for said second member to guide said second member in its direction of movement.

18. In a typewriting machine, a plurality of bars arranged side by side for limited movement in a longitudinal direction, a plurality of members arranged side by side in said machine transverse to said bars and arranged for limited movement towards and away from said bars, each of said bars having a cam slot therein at a point on said bar adjacent one of said members, each of said members having a finger extending towards said bars, said finger being at a point to engage one of the cam slots on one of said bars, whereby when one of said members is moved towards said bars the finger on that member will engage the cam slot on one of said bars to cause said bar to move longitudinally, a plurality of types, each type being associated with one of said bars, means to print said types when said bars are moved longitudinally, and key means to move said members towards said bars.

19. In a typewriting machine, a frame, a rod extending across said frame at the rear thereof, a second rod extending across said frame at the front thereof, a lever pivotally mounted on said first rod, a second lever pivotally mounted on said second rod, a member pivotally mounted on the ends of said levers, the ends of said levers being spaced from each other and lying along a line substantially perpendicular to said levers, means to move said member in one direction guided by said levers, resilient means to urge said member in the opposite direction, a second member mounted adjacent said first member and arranged for limited movement in a direction substantially perpendicular to the direction of movement of said first member, a cam slot in said second member, a finger on said first member and adapted to engage said cam slot when said first member is moved so as to move said second member, a type, and means to print said type when said second member is moved.

20. A typewriting machine for printing type characters simultaneously across a strip comprising

ing an elongated frame, a keyboard arranged at the top of the frame and of substantially the same length as the frame, said keyboard including rows of depressible keys extending lengthwise of the frame, a platen arranged at one end of the frame and positioned transversely of the rows of keys, a plurality of types cooperating with said platen and arranged transversely of the frame at one end thereof, and means arranged substantially directly beneath said keyboard and operatively connecting said types and keys.

21. A typewriting machine for printing type characters simultaneously across a strip comprising an elongated frame, a keyboard arranged at the top of the frame and of substantially the same length as the frame, said keyboard including a plurality of depressible keys arranged in rows extending lengthwise of the frame, a platen arranged at one end of the frame and positioned transversely of the rows of keys, a plurality of types arranged at said end of the frame and movable toward and away from the platen, and means arranged substantially entirely directly beneath the keyboard and operatively connecting said types and keys.

22. In a typewriting machine, an elongated keyboard having depressible keys arranged in rows extending lengthwise of the keyboard, said machine being adapted to be positioned in front of the operator with the long way of the keyboard extending from side to side, a platen arranged at one end of the machine and positioned transversely of the rows of keys, a plurality of types cooperating with said platen and arranged at one side of said machine adjacent an end of the keyboard, said types being mounted for movement in vertical planes extending lengthwise of the keyboard, and means arranged substantially entirely directly beneath the keyboard and operatively connecting the types and keys for causing movement of said types in said planes.

23. In a typewriting machine for printing a plurality of types simultaneously across a strip of paper, a frame, a group of keys mounted in said frame for movement in substantially vertical planes, said frame conforming in shape to the general outline of the group of keys and being slightly larger than said group of keys, a plurality of key levers, each of said keys being mounted on a key lever, a pair of lever arms having one end of each pivotally mounted on said frame and the other end pivotally connected to said key levers, whereby said key levers will have substantially straight line movement and the angularity of the key will not be substantially altered when said key is moved, a plurality of type carriers mounted side by side adjacent said frame, a type carried by each of said type carriers, said types being arranged in a straight line across and adjacent to one of the sides of said frame, means to hold a paper strip in a position to be struck by said types when said type carriers are moved in the proper direction, and means arranged substantially entirely directly beneath the keyboard, connected to said key levers and cooperating with said type carriers, to cause a type carrier to move when its key is depressed, so as to print the type carried by said type carrier.

ROBERT THOMAS POLLOCK.
